UNITED STATES PATENT OFFICE.

ISRAEL DOUCETTE, OF FALL RIVER, MASSACHUSETTS.

WEAVING SHUTTLE-REFINISHING MACHINE.

Application filed June 9, 1924. Serial No. 718,943.

This invention relates to machines for refinishing shuttles used in weaving machines, whereby the life of a shuttle is materially increased.

An object of the invention resides in providing a machine which is adapted to refinish shuttles used in weaving machines, in order to remove rough and splintered surfaces thereof, so that the shuttle will not catch and break previously woven threads. Another object of the invention resides in providing a shuttle refinishing machine for wearing the surfaces of shuttles, and for removing splinters and roughness from the surfaces of the shuttles, and provide a smooth exterior surface thereon, which consists in providing a carrier for mounting the shuttle, adjustable relative to a disc, faced with sand paper and rotatable during the refinishing operation, so that the carrier may be positioned in spaced parallel relation, with respect to the disc, in order that the shuttle may be reversed during the refinishing operation of the several sides and properly squared during the operation.

The invention further comprehends the provision of a machine having a pair of bar members mounting suitable block members in spaced relation, carrying bearings for the shafts, mounting the rotatable disc having the sand papered surface, one of said bearings being of an adjustable character, adapted to take up endwise play in the shaft, while the other bearing includes a thrust bearing portion adapted to receive the thrust from the thrust collar on the shaft, in order that the face of the rotatable disc will be maintained in proper parallel relation with the shuttle carrier and adjustable on a suitable bracket mounted on the bar members between the block members, providing for accurately squaring the shuttle members, while refinishing the same.

The invention also comprehends other objects and improvements in the construction and arrangement of the parts of the device, to produce a simple and inexpensive construction for carrying out the operation of refinishing shuttles, which are more particularly pointed out in the following description and claim, directed to a preferred form of the invention, it being understood, however, that various changes in the details of construction and arrangement of the parts

may be made without departing from the spirit and scope of the invention as described and claimed.

In the drawings, forming a part of this application:

Figure 1 is a plan view of the shuttle refinishing machine.

Figure 2 is an end elevation of one end of the machine.

Figure 3 is a side elevation of the machine.

Figure 4 is an elevation of the other end of said machine.

A pair of bar members are indicated at 1, which are mounted in spaced relation on suitable end blocks 2, through the medium of securing bolts and nuts indicated at 3, cooperating with suitable washers 4, the end blocks being adapted to be secured to suitable floor or other supports, in order to provide a mounting for the machine. Block members 5 are mounted in spaced relation, adjacent the opposite end portions of the bar members 2, at one end, as indicated at 6, while the opposite ends of the block members project to one side of the bar members, for rotatably mounting a shaft 7, one of the block members carrying a pair of spaced bearings 8, rotatably receiving the shaft and mounting the same on the block member and between which a pulley 9 is mounted on the shaft, for receiving a belt from a suitable source of power, one of the bearings 8 being adapted to receive the thrust collar 10 on the shaft 7, in the manner clearly illustrated in Figure 1. The opposite end of the shaft is provided with a conical recess, for receiving the pointed end of a thrust take up pin 11, which is screw threaded and mounted in a bracket 12, mounted on the other block member 5, a lock nut 13 being provided for locking the thrust take up pin, in such position, so that there will be no end play or looseness in the mounting of the shaft 7.

A disc is mounted on said shaft adjacent one end thereof, which is indicated at 14, and which has one surface or face provided with a sand paper covering, as indicated at 15, the disc being mounted on the shaft, in any suitable manner, well known in the art.

A bracket or rest 16 of angular form is provided with a securing foot 17, secured in a suitable manner to the bar members 1, for supporting one portion of said rest, in a substantially horizontal position, above

the shaft 7, on which is mounted a carrier bar 18 for a shuttle. At the lower edge, the bar 18 is provided with laterally extending feet 19, slotted as indicated at 20, to receive securing bolts 21, for holding the bar in a proper position of adjustment on the rest 16, and for guiding the same in its movement toward or away from the disc 14.

- In refinishing a shuttle with this machine, 10 the holder bar 18 is positioned parallel to the face of the disc 14 at a distance slightly less than the width of the shuttle to be refinishing, and tightly secured in place, after which the shuttle is positioned on the rest 15 16, between the sand paper covered face 15 of the disc and the rest 18, and moved across the rest between these elements, during the rotation of the disc, from a suitable source of power, at which time the sand paper will 20 smoothly refinish one surface of the shuttle. Following this, the shuttle is turned over to present another face to the sand paper surface of the disc, following which the above described operation is repeated, for 25 refinishing this last mentioned surface of the shuttle, so that it will be seen that by repeating the operation all of the surfaces of the shuttle presented to the thread during the weaving operation will be smooth and free 30 from splinters and the like, which frequently cause breakage of the thread. In this way, old shuttles can be refinished when required, so that the life thereof is substantially prolonged. The holding bar 18 is adjustable 35 relative to the rest, so that the same may be

set for varying sizes of shuttles, in an obvious manner.

From the foregoing description, it will be clear that a simple and efficient form of machine has been provided, which may be 40 constructed at small cost, for refinishing shuttles of weaving machines, in order to prolong the useful life of the same.

What is claimed is:

A device of the class described, including 45 bar members, a pair of blocks mounted in spaced relation on said bar members and secured thereto at one end, shaft bearings mounted on one of said bar members, a shaft rotatably mounted on said bearings 50 having a thrust collar adapted to engage one of said bearings, for receiving the end thrust of said shaft, an adjustable bearing member on the other block member for the other end of said shaft, adapted to hold the thrust 55 collar in engagement with the bearing, to prevent axial movement thereof in said bearing, a disc mounted for rotation on and with said shaft, having one face thereof provided with abrasive material, a work rest mounted 60 on said bar members, and a holding plate adjustably mounted on said rest adapted to be positioned in parallel spaced relation with respect to the abrasive covered face of said disc member, whereby shuttles may be passed 65 between said disc and holding plate to have the surfaces thereof squared and refinished.

In testimony whereof I affix my signature.

ISRAEL DOUCETTE.
